ARVID H. NERO, OF NEW BRITAIN, CONNECTICUT, ASSIGNOR TO THE ARROW ELECTRIC COMPANY, OF HARTFORD, CONNECTICUT, A CORPORATION OF CONNECTICUT.

ELECTRIC-LAMP SOCKET.

1,131,541.

Specification of Letters Patent.

Patented Mar. 9, 1915.

Application filed January 9, 1914. Serial No. 811,211.

To all whom it may concern:

Be it known that I, ARVID H. NERO, a citizen of the United States of America, and residing at New Britain, in the county of 5 Hartford and State of Connecticut, have invented a certain new and Improved Electric-Lamp Socket, of which the following is a specification.

My invention relates to electric lamp 10 sockets and the object of my invention is to provide a simple and efficient device for locking a lamp in inserted position.

In the accompanying drawings, Figure 1 is a side elevation of a socket in which my 15 invention is embodied in one form; Fig. 2 is a partial section at right angles to Fig. 1 showing the operation of this locking device; Fig. 3 is a detached partial section showing the elements of the locking device; 20 Fig. 4 is a detached elevation of the shell terminal and locking plate of the socket; and Fig. 5 is a vertical section through the shell of a lamp socket showing a modified form of locking screw, the latter being 25 shown detached from its boss.

The present invention may be applied to 30 sockets of various types, but is here applied for the sake of illustration, to a key socket of ordinary type, comprising the usual cap 10 and shell 11 forming a casing through which projects the usual switch key 12. The insulating socket body 13 within the casing carries the screw shell 14 forming one of the 35 terminals for the threaded base 15 of an incandescent lamp 16 which is screwed therein. An insulating lining 17 surrounds the screw shell 14 and insulates it from the shell 11 of the casing.

To prevent the unauthorized removal of a 40 lamp from the socket after insertion, I form an aperture 18 in the screw shell 14 at a convenient point, preferably in line below the key 12, since the latter is always placed in accessible position, and arrange upon the 45 socket in any suitable manner a clamping plate 19 a portion of which is adapted to be projected through the aperture 18 in the screw shell and bear against the inserted lamp base. As here shown the clamping plate 50 is riveted at its upper end 20 to the screw shell and its lower end is roughened at 21 to afford a better grip upon the lamp base. Any suitable means may be employed 55 to force this clamping plate against the lamp base. The means here shown, comprise a

locking screw 22 carried by an internally threaded boss 23 mounted on the shell casing 11 in register with the aperture 18, and provided with any suitable means, such as the triangular stem 24 for the reception of a 60 key 25. As the locking screw 22 moves inward it bears against the clamping plate 19 through the insulating lining 17 and forces the plate through the aperture 18 into engagement with the lamp base, thus locking 65 the latter against withdrawal. To free the lamp it is of course only necessary to turn the screw outward thus releasing the pressure upon the plate 19, and permitting the lamp to be unscrewed. As a simple modification of this type of locking screw I have shown in Fig. 5 spindle 26, the head of which is provided with a cam face 27 bearing against a co-operating cam face 28 on the inner end of the boss 29. The pitch of 70 these cam faces is such that the head of the locking screw is advanced and retracted more rapidly than would be the case with screw 22 above described, unless the pitch of the thread of the latter were made unusually high. No means, other than the insulating lining 17 of the socket, is needed to prevent the locking spindle from falling 75 into the interior of the socket. Various other means may be provided for forcing 80 the clamping plate inward against the lamp base and I do not limit my invention to the particular constructions shown.

I am aware that others have heretofore proposed to lock the lamp against withdrawal by means of set screws or the like piercing the insulating lining of the socket and the screw shell terminal. So far as I am aware however, no one has hitherto arranged inside the lining a clamping plate 90 or the like which is forced against the lamp base by pressure against the insulating lining, thus completely obviating the danger which results from contact with the electrically alive terminal of the lamp base. 100

I claim as my invention:—

1. An electric lamp socket comprising a metallic casing, an insulating lining therefor, an apertured terminal for a lamp base within said lining, a clamping plate supported within said lining and having a portion lying in register with the aperture in the lamp terminal, and locking means carried by the socket casing and bearing upon the outer face of said insulating lining but 110

in register with the free end of said clamping plate to force the latter through the apertured terminal into engagement with the lamp base to lock the latter against withdrawal.

2. An electric lamp socket, having an apertured screw shell terminal for a lamp base, a clamping tongue extending into said aperture, a socket casing surrounding said shell terminal, an insulating lining interposed between said casing and terminal, and means carried by said casing and bearing upon the outer face of said lining but in register with the free ends of said clamping tongue to force the latter into engagement with a lamp base inserted in said terminal and lock the same against withdrawal.

3. An electric lamp socket comprising an apertured screw shell terminal, a clamping piece adapted to be advanced through the aperture in said terminal into engagement with an inserted lamp base, a socket casing surrounding said terminal and means carried by said casing in register with the aper-

ture in said screw shell terminal and insulated from said clamping piece for forcing the latter into engagement with the lamp base to lock the latter against withdrawal.

4. An electric lamp socket comprising a screw shell terminal having an aperture in the side thereof, a clamping plate secured to said shell and having a portion in register with said aperture, a socket casing surrounding said screw shell, insulating material between said terminal and casing, in combination with a locking screw carried by said casing in register with the aperture in the terminal and bearing upon the outer face of said insulating material but in register with the free end of the clamping plate to force the latter inward, for the purpose described.

In testimony whereof I have signed my name to this specification, in the presence of two subscribing witnesses.

ARVID H. NERO.
